UNITED STATES PATENT OFFICE.

HENRY WILDBERG AND FRED W. HOELTGE, OF CINCINNATI, OHIO, ASSIGNEES TO
WILDBERG BOX COMPANY, OF CINCINNATI, OHIO, A FIRM COMPOSED OF HENRY
WILDBERG AND SAMUEL H. WILDBERG.

BOTTLE-CONTAINER.

1,881,807.

Specification of Letters Patent. Patented Feb. 24, 1920.

Application filed May 16, 1919. Serial No. 297,660.

To all whom it may concern:

Be it known that we, HENRY WILDBERG and FRED W. HOELTGE, residents of the city of Cincinnati, in the county of Hamilton 5 and State of Ohio, and citizens of the United States, have made certain new and useful Improvements in Bottle-Containers, of which the following is a full, clear, and exact description, reference being had to the 10 accompanying drawings, forming a part of this specification.

Our invention relates to containers adapted for use with bottles, and more particularly the type of bottles used in the sale of 15 milk, buttermilk and the like. It has been the practice in recent years to make up such boxes with an open top and bottom, and crossed wire or rods through the inside of the box to hold the bottles separated from 20 each other in upright position.

It is the object of our invention to provide a container of this special character which is strong and secure, and holds bottles of the nature above noted, in a manner to make 25 them quickly and readily available, and secure during shipment or transportation. More particularly, it is our object to provide a bracing member for such boxes which is simple and easily attached and co-operates 30 with the cross rods in its operation.

These objects we accomplish by that certain construction and arrangement of parts to be hereinafter more specifically pointed out and claimed.

35 In the drawings,

Figure 1 is a perspective view of the box with the side wall broken away to show the construction of the brace.

Fig. 2 is a vertical section through the 40 box, on line 2-2 of Fig. 1.

The box is shown as having the four sides, 1, and is open at the top and bottom. On the upper corners of the device are located the angle shoulder plates 2 which are adapted 45 to engage within the walls of another like container upon shipment. Extending lengthwise and crosswise of the container are the rods 3 and 4 respectively, these rods forming compartments for the reception of 50 milk bottles 5.

These rods 3 and 4 are securely held in place by passing them through the walls of the container, and riveting the ends as shown at 6. Prior to mounting the rods,

however, they are inserted through the 55 brace which is the more particular concern of this invention.

The brace comprises vertical arms 7, 7, which have knuckles 8 at their upper ends to receive the central cross rod, 4 of the device. 60 Just below the knuckles are located suitable holes (not shown) to permit the passage of the rods 3, 3.

At the lower ends of the arms 7, they are bent at an angle as shown at 9, and suitably 65 secured to the inverted trough or angle strip 10. This strip 10 straddles the lower central cross rod 4, and has slots 11 properly located to permit the passage of the lower lengthwise rods 3 through the slots, but be- 70 low the said lower cross rod.

The fit of the rods in the bracing device as now described can be made fairly tight, and it will be observed that the result will be a very firm bracing of the box, through 75 the interlacing of the cross rods, and the tying of them together.

The number of cross rods, or arms to the brace and the exact central location of the brace or the number of braces used in the de- 80 vice do not form essential parts of our invention. The angle strips at the lower portion of the brace should preferably fit snugly against the sides of the container. The conformation of the box generally forms no requisite 85 feature of the novel device.

Having thus described our invention, what we claim as new and desire to secure by Letters Patent is:—

1. A brace for bottle containers having 90 bottle compartment forming rods comprising arms adapted to tie together the cross- wise and lengthwise rods at the upper portion of the box and a member extending across the box and secured to said arms for 95 tying together the said rods at the lower portion of the box.

2. A brace for bottle containers having bottle compartment forming rods comprising an angle strip adapted to fit over a rod 100 running in one direction across the box, and having slots therein to receive the rods running counter to said first mentioned rod, in a position of engagement under said first rod.

3. A brace for bottle containers having 105 bottle compartment forming rods comprising an angle strip adapted to fit over a rod running in one direction across the box, and

having slots therein to receive the rods running counter to said first mentioned rod, in a position of engagement under said first rod, arms connected to said angle strip, said arms 5 adapted to receive at another portion thereof two intersecting rods.

4. A container for milk bottles or the like comprising lateral walls, compartment

forming rods in a plurality of horizontal planes extending across the said box, and 10 secured to the wall thereof, and a brace for tying said rods together at a plurality of intersecting points in both of the planes.
